BED COVER OR SIMILAR ARTICLE

Lillard Franklin McCloud, New York, N. Y., assignor to Pepperell Manufacturing Company, Boston, Mass., a corporation of Massachusetts

Application December 11, 1957, Serial No. 48,861

Term of patent 3½ years

Figure 1 is a perspective view of a bed cover, showing my new design as it appears upon a bed, the dotted indication of the headboard being included for illustrative purposes only; and Figure 2 is a plan view of the bed cover shown in Figure 1, showing one complete repeating unit in full lines, which unit is repeated in regular succession as indicated by the extensions beyond the unit boundaries; said unit constitutes one-sixth of the bed cover and is repeated twice horizontally and three times vertically.

I claim:

The ornamental design for a bed cover or similar article, as shown and described.
